UNITED STATES PATENT OFFICE.

BENJAMIN F. OSBORN AND EMIL F. ZIRBEL, OF RIPPEY, IOWA.

TRAIN-LOCATING AND TIME-RECORDING APPARATUS.

1,091,756.

Specification of Letters Patent. Patented Mar. 31, 1914.

Application filed February 8, 1911. Serial No. 607,886.

To all whom it may concern:

Be it known that we, BENJAMIN F. OSBORN and EMIL F. ZIRBEL, citizens of the United States of America, and residents of Rippey, Greene county, Iowa, have invented a new and useful Train-Locating and Time-Recording Apparatus, of which the following is a specification.

The object of this invention is to provide an improvement in the art of recording and annunciating the location of railway trains throughout a division or system of a railway.

A further object of this invention is to provide an improvement in the art of recording and annunciating the time at which various railway trains are in various stations throughout a division or system of a railway.

20 A further object of this invention is to provide an improvement in the art of recording and annunciating the location and time of a series of railway trains at or in a series of stations throughout a division or 25 system of a railway, the time and location being recorded and annunciated simultaneously with each other and practically simultaneously throughout the series of stations.

30 A further object of this invention is to provide means adapted for operation by a trainman at successive stations whereby the location of his train and the time of its arrival to such stations may be recorded and 35 announced at the several stations touched by the train.

A further object of this invention is to provide means adapted for operation by a trainman at successive stations whereby the 40 location of his train and the time of its arrival to such stations may be simultaneously recorded and announced at the several stations touched by the train.

45 A further object of this invention is to provide means adapted for operation by trainmen at successive stations whereby the locations of their trains and the time of their arrival to such stations may be recorded and announced at the several stations touched by the trains.

50 A further object of this invention is to provide means adapted for operation by trainmen at successive stations whereby the locations of their trains and the time of 55 their arrival to such stations may be simul-

taneously recorded and announced at the several stations touched by the trains.

Our invention consists in the construction, arrangement and combination of elements hereinafter set forth, pointed out in our claims and illustrated by the accompanying drawing, in which—

Figure 1 is a diagram illustrating a series of electrically connected groups of annunciators, which annunciators each contain a key-operated switch and a clock-controlled dating mechanism. Fig. 2 is an elevation, partly in diagram, of a single group of annunciators associated with a single clock, each annunciator having a clock-controlled dating mechanism and a key-operated switch. Fig. 3 is an elevation of part of the devices shown in Fig. 2 at right angles to such showing. Fig. 4 is a plan of the devices shown in Figs. 2 and 3. Fig. 5 is an enlarged front view of one of the annunciators. Fig. 6 is a front view, partly in section, of part of the devices shown in Fig. 5, the front closing means being removed. Fig. 7 is a vertical section of the remaining parts of the annunciator shown in Fig. 5. Fig. 8 is a vertical section illustrating a means employed to connect clock mechanism in driving relations with dating mechanism.

In the apparatus or system as illustrated, stations A, B, C, D, E, corresponding in number with the railway stations of a division or operating section of a railway, are each provided with a group of annunciators, each group corresponding in number with the trains operating in each division or section; and each station or group of annunciators also includes a timing mechanism. The annunciators are electrically connected in series, each series including one annunciator of each group, throughout the length of the division or section, and each series of annunciators is independent of each other series and each timing mechanism is normally independent of the annunciator circuits and of each other and each annunciator circuit normally is closed. Each annunciator is provided with a time-mechanism-controlled recording mechanism and a key-operated switch.

The key-operated switches of a series of annunciators are all susceptible of operation by a key of one form, which key differs in form from those employed to oper-

ate the switch of the other series, and said key is carried by a trainman, preferably the conductor in charge. When a train is about to leave the terminal station of a 5 division the trainman uses his key to operate a switch of the annunciator at that station applicable to his train, and in so doing breaks the circuit of the series of annunciators applicable to his train throughout the 10 entire division or section; such breaking of the circuit setting up in each annunciator of the series an operation of the recording mechanism which will record a visible memorandum of the time at which such operation 15 by the trainman is effected, in each annunciator of the series, thus electrically and automatically announcing in a visible printed record the time of departure, of the train on a trip through its division or 20 section. This operation is repeated by the trainman at successive stations throughout the trip and at each operation the time of such operation is automatically and electrically recorded and exhibited at all of the 25 stations covered by such trip. The indicated trainman of the next succeeding train leaving the terminal performs the same operation in respect of another series of annunciators and so on through the series of 30 trains and independent series of annunciators applicable thereto to the full number of trains traversing such division or section. It is to be understood that the timing mechanism at a given station is common 35 to all of the annunciators and recording mechanisms therein located at such station and that such timing mechanism is operated independently of the annunciator circuits. In the drawings (Figs. 1 and 2) 40 the annunciators of the various series are designated by letters *a*, *b*, *c*, *d* and *e* and the various timing mechanisms generally by the indices *A'*, *B'*, *C'*, *D'*, *E'*, the circuits connecting the annunciators in series being 45 designated by the indices *a'*, *b'*, *c'*, *d'*, *e'*.

Each annunciator *a*, *b*, *c*, *d*, *e* is constructed with a housing 10 having a glazed door 11 forming a closure for its front, said door being secured in a closed position 50 by a key-operated lock 12; a switch box 13 depending from or located immediately beneath the housing 10; and a clock box 14 surmounting the housing 10 or located immediately above it and carrying a glazed 55 dial 15. The switch box 13 contains a fixed contact member 16 and a movable contact member 17 adapted to contact normally with the first member, said members being in the electric circuit *a'*, *b'*, *c'*, *d'* or *e'* as the case may be. The movable contact member 17 is fixed to and adapted to be moved by a tumbler 18 to break the circuit by breaking the contact between the members, and said tumbler extends through 60 the front wall of the switch box 13 and is

adapted to receive the trainman's key (not shown). It is to be understood that the tumbler 18 is shown conventionally and may vary in form as desired, the tumblers of the series *a*, *b*, *c*, *d*, *e* differing from each other in the shape of key required to operate them. A shaft 19 is mounted through all of the housings 10 of a group at a station such as A, B, C, D or E and is adapted to be rotated continuously or intermittently 70 as to minute intervals of time by gearing to a rod 20 extending into the clock box 14 and connected to the clock mechanism, the gearing between said shaft and rod being shown conventionally and designated by the 75 numeral 21 in Fig. 8. A shaft 22 extends through all of the housings 10 of a given group of annunciators, preferably parallel with and above the shaft 19, and a series of printing wheels 23 are mounted on said 80 shaft 22 within each of the housings and carry type for printing names of stations and times of day respectively. The shaft 22 or the printing wheels 23 thereon are independently rotated intermittently by 85 gear connections with the shaft 19, said gear connections being shown conventionally in Fig. 7 and designated by the numeral 24. We have not shown nor described the details of construction of the printing wheels 90 23 or gear connections 24 as they form no part of our present invention and various recording devices, registering devices and the like now on the market and well known may be adapted to this purpose and be 95 mounted in the housings 10. A spool 25 is mounted in the lower portion of each housing 10 and a ribbon or tape 26, preferably of paper, is wound on said spool. The bight of the ribbon or tape 26 is carried over a direction roller 27 in the upper portion of the housing 10 and an end portion of said tape is carried and fixed and adapted to be wound on a spool 28 also located in the upper portion of the housing and at the rear of the 100 direction roller. The spool 28 preferably is fixed to and carried by a spring drum 29 of conventional form, adapted to be operated in one direction by a spring contained in said drum for the purpose of winding the ribbon or tape 26 on said spool and unwinding the same from the spool 25. A ratchet 30 is formed on the spring drum 29 and a detent 31 mounted within the housing normally engages said ratchet and prevents rotation of the ratchet, drum and spool under impulse of the spring in the drum. A bight portion of the ribbon or tape 26 between the spool 26 and roller 27 extends vertically in 105 proximity to but out of contact with the printing wheels 23 and the face of said ribbon or tape opposed to the printing wheels and also opposed to and visible through the glazed portion of the door 11, preferably is 110 printed with columnar spaces respectively 115 120 125 130

adapted to receive from the printing wheels imprints of station names and time records. Corresponding indications, such as "Stations" and "Time" may be placed on the 5 glazed portion of the door 11 in front of the columnar spaces indicated on the ribbon or tape 26. In this connection attention is called to a legend, such as "Train No. 1", which may be placed on the upper portion 10 of the door 11 of an annunciator to guide an inquirer. An armature 32 is mounted for rectilinear reciprocation at right angles to and at the rear of the shafts 22, 24 and said armature carries a platen 33 on one end. 15 The platen 33 is formed with guides through which the ribbon or tape 26 passes vertically and said platen is on the opposite side of said ribbon or tape from the printing wheels 23. A coil magnet 34 is mounted loosely 20 around the armature 32 and is in circuit with the electric circuit a', b', c', d' or e' as the case may be. The armature 32 is formed with a longitudinal slot 35 and a pin 36 extends through said slot and through a 25 bearing within which the armature reciprocates. A spring 37 is interposed between the pin 36 and armature 32 and normally acts to move the armature in such direction as to withdraw the platen 33 from the printing 30 wheels 23. A spring 38 is mounted in another bearing of the armature and presses against the rear end of said armature. The 35 detent 31 is formed with a fork embracing the rear end portion of the armature 32 and engaging a pin 39 extending through said 40 armature. The spring 39 also engages the adjacent bearing and determines the degree of compression of the spring 38 by limiting movement of the armature in one direction. 45 While the electric circuit is closed and the coil magnet 34 is energized there is a tendency of the armature 32 to center in said coil magnet and compress the spring 38, thus permitting the detent 31 (under pressure of a spring 40 on its pivot) to engage 50 the ratchet 30. When the circuit is broken, however, by key operation of the tumbler 18 and switch member 17, the coil magnet 34 is deenergized and the spring 38 expands 55 suddenly and forcibly, thus moving the armature 32 and platen 33 forwardly and impacting the tape or ribbon 26 with the printing wheels 23. Immediately upon this operation the spring 37 (which is compressed by 60 expansion of the spring 38) reacts or rebounds on the armature 32 and moves it rearwardly sufficiently to separate the ribbon or tape 26 from the printing wheels, thus imprinting said tape with a station 65 name and time by said wheels. Immediately upon release of the tumbler 18 by cessation of the manual movement thereof through the key, the contact member 17 falls by gravity into contact with the member 16, closes 70 the circuit, and the coil magnet 34 is again

energized and moves the armature 32 to initial position and compresses the spring 38. Momentarily at a point in the operation of the printing devices the detent 31 is withdrawn from the ratchet 30 by the pin 39 and the ribbon or tape moves a distance sufficient to bring the printed record into view 75 behind the glazed portion of the door 11.

Any desired devices and mechanisms may be employed for setting the printing wheels forwardly in unison with the travel of the hands of the clock; any desired mechanisms or devices may be employed for causing the printing wheels to imprint the stations and time on the ribbon or tape; any desired devices may be employed for advancing the ribbon or tape from spool to spool; and any desired devices may be employed for breaking the circuit. Therefore, we do not desire to be understood as limiting ourselves to the 80 precise construction and arrangement of parts shown since the several devices may be modified at will without departing from the spirit of our invention.

If desired the station names may be 85 printed, in the proper order, on the ribbon or tape, in such position as to come within the column for "Stations;" and the ribbon or tape may be extended to such length as to accommodate a number of complete lists of 90 such names of stations, for instance sufficient to last for a month's business. In the event this plan is used, the printing wheels 23 would be used only for printing the times 95 of day.

100 We claim as our invention—

1. An improvement in the art of recording and annunciating the location of railway trains, which improvement consists of a series of electrically connected annunciators, 105 key-operated means associated with each annunciator for operating the entire series of annunciators simultaneously, and recording devices associated with each of said annunciators.

2. An improvement in the art of recording and annunciating the location of railway trains, which consists of a series of electrically operated annunciators in closed circuit, key-operated means associated with 110 each annunciator for breaking said circuit, and dormant recording devices associated with each annunciator and operated only during the time the circuit is broken.

3. An improvement in the art of recording 115 and annunciating the location of railway trains, which consists of a series of electrically operated annunciators in closed circuit, means associated with each annunciator for breaking said circuit, and recording devices associated with each annunciator and operated during the time the circuit is 120 broken.

4. An improvement in the art of recording 125 and annunciating the location of railway

trains, consisting of a series of stations, each station having a number of annunciators corresponding with the number of trains operated to or through said station, said 5 annunciators arranged in independent series in closed circuits throughout the several stations, one annunciator of each series being located at each station, key-operated means associated with each annunciator for breaking the circuit thereof, recording means in 10 each annunciator, and means for operating the recording means during the time the circuit is broken.

5. An improvement in the art of recording 15 and annunciating the location of railway trains, which improvement consists of a series of electrically connected annunciators, means for operating the series of annunciators simultaneously, and separate recording 20 and exhibiting devices associated with each of said annunciators, and all adapted to be operated by operation of one set thereof.

6. An improvement in the art of recording 25 and annunciating the location of railway trains, which consist of a series of electrically operated annunciators in closed circuit, means for breaking said circuit, and separate recording and exhibiting devices associated with each annunciator and simultaneously operated only during the time the 30 circuit is broken.

7. An improvement in the art of recording 35 and annunciating the location of railway trains, which consists of annunciators in series at successive stations, recording means associated with said annunciators, and means at each station adapted for operation by a trainman whereby the location of his train and the time of its arrival may be recorded and announced at the several stations in such series.

8. An improvement in the art of recording 45 and annunciating the location of railway trains, which consists of annunciators in series at successive stations, recording means associated with said annunciators, and means at each station adapted for operation by a trainman whereby the location of his train and the time of its arrival may be simultaneously recorded and announced at 50 the several stations in such series.

9. An improvement in the art of recording 55 and annunciating the location of railway trains, which consists of annunciators in series at successive stations, recording means associated with said annunciators, and means at each station adapted for operation by trainmen whereby the locations of their trains and the time of their arrival may be simultaneously recorded and announced at 60 the several stations in such series.

10. An improvement in the art of recording 65 and annunciating the location of railway trains, which consists of annunciators in series at successive stations, recording

means associated with said annunciators, and means at each station adapted for operation by trainmen whereby the locations of their trains and the times of their arrival may be recorded and announced at the several stations in such series. 70

11. An improvement in the art of recording 75 and annunciating the location of railway trains, which consists of a series of annunciators at separated stations in a closed electric circuit, recording devices in each annunciator, exhibiting devices in each annunciator, means for advancing the exhibiting devices, means for operating the recording devices, and key-operated circuit-breaking devices in each annunciator adapted to act on the circuit of the entire series of annunciators. 80

12. An improvement in the art of recording 85 and annunciating the location of railway trains, which consists of a series of annunciators at separated stations in a closed electric circuit, recording devices in each annunciator, exhibiting devices in each annunciator, means for advancing the exhibiting 90 devices, means for operating the recording devices and key-operated circuit-breaking devices in each annunciator adapted to act on the circuit of the entire series of annunciators, the circuit-breaking devices being automatically operated to make the circuit. 95

13. An improvement in the art of recording 100 and annunciating the location of railway trains, which consists of a series of electrically connected annunciators, means for operating the series of annunciators simultaneously, separate recording devices associated with each of said annunciators, the recording devices of all the annunciators adapted to be operated by actuation of any 105 selected one, and a separate timing mechanism for each annunciator and acting on the recording devices.

14. An improvement in the art of recording 110 and annunciating the location of railway trains, which consists of a series of electrically operated annunciators in closed circuit, means for breaking said circuit, recording devices associated with each annunciator and conjunctively operated during the 115 time the circuit is broken, and timing mechanism acting on the recording devices.

15. An improvement in the art of recording 120 and annunciating the location of railway trains, which consists of annunciators in series at successive stations, recording means associated with said annunciators, timing mechanism acting on the recording devices, and means at each station adapted for operation by a trainman whereby the location of his train and the time of its arrival may be recorded and announced at 125 the several stations in such series.

16. An improvement in the art of recording 130 and annunciating the location of rail

way trains, which consists of groups of annunciating stations, closed electric circuits each of which connects a unit of each group, recording devices common to each group, timing mechanisms common to each group and acting on said recording devices, and means for selectively breaking the circuit of either series of units.

17. An improvement in the art of recording and annunciating the location of railway trains, which consists of a series of annunciators in a closed circuit, a printing device in each annunciator, a ribbon and feeding devices therefor in each annunciator, means for contacting the ribbon and printing devices in each annunciator, a timing device acting on the printing device, and a key-operated switch in each annunciator.

18. An annunciator comprising a housing,

recording and exhibiting devices in said 20 housing, timing mechanism acting on the recording devices, electrical controlling devices for said recording and exhibiting devices, and a key-operated switch acting on said electrical controlling devices.

19. A series of annunciators in a closed electric circuit, each annunciator having recording and exhibiting devices, a timing device acting on the recording devices, and a key-operated switch acting to break said circuit.
